FURNACE COVER OPERATING MECHANISM

Carl H. West, St. Clairsville, Ohio, assignor to
 Blaw-Knox Company, Pittsburgh, Pa., a corporation of New Jersey

Application December 1, 1944, Serial No. 566,155

3 Claims. (Cl. 268—10)

1

This invention relates to furnace cover operating mechanism. It relates particularly to mechanism for moving a furnace cover between open and closed positions. The invention is especially applicable to mechanism for operating covers which close generally upwardly open furnaces, such, for example, as pit type furnaces. The invention is herein shown and described as applied to mechanism for operating the cover of an ingot heating furnace.

Various mechanisms have heretofore been utilized for operating the covers of generally upwardly open furnaces. It is desirable in the operation of such furnace covers to first raise the cover out of contact with the furnace and then move the cover laterally to clear the furnace opening. The mechanisms heretofore employed for thus operating furnace covers have been, generally speaking, complicated and expensive and likely to become out of order or to deteriorate in use. The furnace heat tends to warp the cover operating mechanism and makes it extremely difficult to maintain lubrication of parts.

I provide a furnace cover operating mechanism of extremely simple and inexpensive design and which accomplishes its function in a highly effective manner. The parts are few and are not of complex design. No lubrication of parts subjected directly to furnace heat is essential. The parts are such that any slight warping thereof in use does not detrimentally affect the operation of the mechanism.

I provide track means upon which the furnace cover may be moved laterally between closed and open positions and I arrange the track means so as to be raised and lowered whereby to raise the cover clear of the furnace before it is moved laterally to expose the furnace opening and to lower the cover into engagement with the portion of the furnace surrounding the opening after it has been returned to position over the opening. I provide track means movable between a lower position out of contact with the cover while the cover is resting on the furnace and an upper position in contact with the cover in which the track means supports the cover out of contact with the furnace. I also provide means for moving the cover along the track means while the track means is in its upper position.

The track means may be movable between its lower and upper positions either by raising and lowering the entire track means or by tilting the track means. For example, the track means may be pivoted at one end and swung about the axis of the pivot in a generally vertical plane, the oppo-

2

site end being disposed above the furnace and carrying the cover when it is disposed above the furnace opening. The track means is preferably raised and lowered by piston means operated by fluid under pressure.

I further provide furnace cover operating mechanism comprising raisable track means adapted to lift the cover to a position in which the cover is substantially spaced from the furnace and means preferably including piston means for moving the cover along the track means. The means for moving the cover along the track means preferably includes a connection maintaining engagement with the cover continuously irrespective of the position of the cover. Such means may, for example, comprise a lever, a link connecting the lever to the cover and means for swinging the lever to move the cover along the track means.

Other details, objects and advantages of the invention will become apparent as the following description of a present preferred embodiment thereof proceeds.

In the accompanying drawings I have shown a present preferred embodiment of the invention, in which

Figure 1 is a side elevational view, partly in vertical cross section, of an ingot heating furnace having a cover operated by my improved cover operating mechanism, and

Figure 2 is a plan view of the structure shown in Figure 1 but to slightly smaller scale.

Referring now more particularly to the drawings, the furnace is built upon a foundation 2 and comprises a hearth 3, side walls 4, end walls 5 and a cover 6 adapted to close the furnace at the top. Burners 7 are mounted in the side walls 4. The gases are drawn off through an offtake 10.

The furnace is disposed generally within a supporting structure designated generally by reference numeral 11, the walls 4 and 5 projecting somewhat above such supporting structure. The supporting structure includes a back-up binding 12 surrounding the walls 4 and 5 near the upper ends thereof. Surrounding the upper ends of the furnace walls 4 and 5 and disposed above the binding 12 is a continuous hollow pipe or conduit 13. As shown in Figure 2, the conduit 13 consists of four lengths of straight pipe cut at 45° angles at their ends and welded together. The pipe or conduit 13 is arranged in a plane parallel to the plane of the binding 12 and also parallel to the plane of the top or rim of the furnace chamber. The upper surface of the conduit 13 is at

an elevation slightly above the upper surface of

the furnace walls, as shown in Figure 1. A structural member 14 is interposed between the conduit 13 and the binding 12. The conduit is mounted on the furnace supporting structure and not upon the refractory wall structure. Yet it surrounds the upper extremity of the refractory wall structure and is in thermoconductive relation therewith so that when cooling fluid passes through the conduit it will cool not only the conduit itself but by conduction through the conduit wall the upper extremity of the refractory portion of the furnace and also, when the cover is in place, the portion of the cover which is in contact or proximity with the conduit. Cooling fluid is circulated through the conduit 13 in any suitable manner, fluid inlet and outlet connections, not shown, being provided.

The cover 6 includes a peripherally extending metal portion 17 whose under surface is smooth and which, as clearly appears in Figure 1, is adapted to rest on top of the conduit 13 when the cover is in place. The central portion of the cover is of refractory material, as are the walls 4 and 5. The cover also includes a metal superstructure 18 extending thereabout. The superstructure 18 carries bearings in which are mounted wheels 19 on which the cover is adapted to be rolled from its position over the furnace opening to a position offset from the furnace opening to permit ingots to be charged into and withdrawn from the furnace. In Figure 1 the cover 6 is shown in closed position in central vertical cross section and it is shown in open position in chain lines.

I provide a foundation 20 having a metal superstructure 21 carrying eyelets 22, one at each side of the superstructure. Pivot to the eyelets 22 by coaxial horizontal pivot pins 23 is a track supporting structure comprising opposed beams 24, one at each side of the furnace. Each of the beams 24 has at its end opposite the end at which it is pivoted to one of the eyelets 22 a bracket 25 to which is pivoted at 26 the piston rod 29 of a piston operable within a cylinder 30 pivoted at 31 to a bracket 32 mounted on the furnace supporting structure 11. Suitable fluid connections and control mechanism, not shown, are provided for the cylinders 30 so that fluid under pressure can be admitted below the pistons in said cylinders to raise the pistons. The connections and control mechanism are such that fluid will be admitted into both cylinders simultaneously below the respective pistons therein and will be discharged from the cylinders simultaneously. When the pistons in the two cylinders 30 are raised the beams 24 are tilted from their full line position to their chain line position viewing Figure 1. In other words, they are swung about the common axis of the pivot pins 23 so that their left-hand ends viewing Figure 1 are raised.

Each of the beams 24 lies beneath the two wheels 19 at one side of the cover 6. Mounted on each beam 24 directly beneath the wheels 19 at the corresponding side of the cover is a track 33. Each track 33 has at each end an upward projection 34 against which a wheel of the cover comes to rest when the cover has moved to its extreme position in that direction, the projections 34 thus serving as stops to limit movement of the cover along the tracks in both directions.

When the beams 24 are in their lowermost position viewing Figure 1, the tracks 33 are out of contact with the wheels 19 and the cover 6 rests upon the pipe 13 so as to close the furnace. When the pistons are raised in the cylinders 30, tilting the

beams 24 as above described, the tracks 33 engage the wheels 19 and raise the cover to a position above and clear of the furnace and in which it is supported on the tracks 33. When the beams 24 are returned to their lowermost position by lowering of the pistons in the cylinders 30 the cover is reseated on the pipe 13 to close the furnace.

The foundation 20 carries a bracket 35 in which is mounted a pivot pin 36 to which are pivoted the lower ends of opposed lever members 37 which together form a composite lever 38. The lever members 37 are spaced apart and one thereof has its lower end offset as shown in Figure 2. The upper end of the composite lever 38 carries a pivot pin 39 to which is pivoted an adjustable link 40. The adjustable link 40 is in turn pivoted at 41 to a bracket 42 connected with and forming a part of the cover superstructure 18.

The foundation 20 carries bearings 43 in which is mounted through trunnions 44 a fluid pressure cylinder 45 within which operates a piston having a piston rod 46 pivoted to the lever 38 at 47. Suitable fluid connections and control mechanisms, not shown, are provided for the cylinder 45 so that fluid under pressure can be admitted at either side of the piston therein to move the piston in either direction as desired.

The lever 38 and link 40 operable by the piston in the cylinder 45 are for the purpose of moving the cover 6 along the tracks 33 between its position above the furnace opening and its position offset therefrom. After the beams 24 have been tilted to their chain line position as shown in Figure 1, fluid is admitted to the left of the piston in the cylinder 45, which moves the piston toward the right, in turn drawing the piston rod 46 toward the right and swinging the lever 38 in clockwise direction about the axis of the pin 36. Since the lever is connected with the cover by the adjustable link 40 it draws the cover with it. The cover moves toward the right until its forward wheels strike the right-hand projections 34 on the tracks 33. The furnace is then open so that ingots may be charged thereto or removed therefrom.

To replace the cover on the furnace fluid under pressure is admitted to the right of the piston in the cylinder 45, viewing Figure 1, while the left-hand end of the cylinder is opened to exhaust. This moves the piston toward the left which, in turn, causes the lever 38 to swing back in the counter-clockwise direction about the axis of the pin 36, pushing the cover 6 back to its position above the furnace opening. The cover stops when its left-hand wheels, viewing Figure 1, strike the left-hand projection 34 on the tracks 33. The fluid below the pistons in the cylinders 30 is then exhausted and the beams 24 settle by gravity to their lowermost positions, depositing the cover on the pipe 13 to close the furnace. The beams 24 swing downwardly slightly farther than the cover so that after the cover has been brought to rest upon the furnace the tracks 33 move out of contact with the cover. Thus any slight warping of the beams or tracks will not result in maintaining the cover in open position.

The structure of the furnace including the provision of the burners 7 is described and claimed in my copending application Serial No. 559,500 filed October 20, 1944, and the furnace closure, including the provision of the pipe 13 upon which the cover rests when in closed position, is described and claimed in my Patent No. 2,407,047, dated Sept. 3, 1946.

While I have shown and described a present preferred embodiment of the invention it is to be distinctly understood that the invention is not limited thereto but may be otherwise variously embodied within the scope of the following claims.

I claim:

1. A furnace cover operating mechanism for a furnace chamber or the like having an opening adapted to be closed by a furnace cover acting under the force of gravity, comprising in combination, a furnace cover adapted to close said opening when in operative position, said cover being further adapted to be substantially entirely removed from said opening by translatory movement only substantially in the plane of the closure effected by said cover, generally parallel rigid tracks extending on opposite sides respectively of said opening and adapted to support said cover during said translatory movement thereof, said tracks extending beyond said opening in the direction of said removal of said cover a distance at least equal to the length of said cover in said direction of movement, spaced supporting members on one side of said cover adjacent at least one of said tracks, at least one supporting member on the opposite side of said cover adjacent at least another of said tracks, said supporting members adapted to be supported on said tracks for substantially rolling engagement therewith during said translatory movement of said cover, means for simultaneously moving said tracks at at least one end thereof when said cover is in operative position in a direction away from the bottom of said opening toward said opening to cause said tracks to engage said supporting members and lift said cover out of said operative position, said means being further adapted to be moved in a direction toward the bottom of said opening to allow said cover to move into operative position and to disengage said tracks from said supporting members, a swingable member pivotally connected to said cover and adapted to move said cover when said tracks have lifted it out of operative position, means for swinging said swingable member, said means being substantially entirely positioned in the direction of the side of the exposed face of said cover when in operative position, whereby said cover in operative position remains unaffected by any warpage in said tracks and upon removal of said cover said cover does not extend substantially beyond the plane it occupied when in operative position.

2. A furnace cover operating mechanism for a furnace chamber or the like which opens upwardly, comprising in combination, a furnace cover adapted to close said opening when in operative position, said cover being further adapted to be substantially entirely removed from said opening by translatory movement only substantially in the plane of the closure effected by said cover, generally horizontal and parallel tracks spaced on opposite sides of said opening and extending beyond said opening a sufficient distance for said substantially entire removal of said cover by said translatory movement, spaced supporting members on each of opposite sides of said cover, said supporting members adapted to be supported on said tracks during movement of said cover, means for simultaneously elevating said tracks at at least one end thereof when said cover is in operative position to cause said tracks to engage said supporting members and lift said cover off said furnace chamber opening, a lever substantially positioned adjacent and below said

5
6
cover, said lever being pivotally fixed adjacent its lower end and linked adjacent its upper end to said cover, means for swinging said lever away from said furnace after said tracks have been elevated, whereby the closure between said furnace cover and said furnace chamber is broken and then said furnace cover is moved entirely to one side of said opening by translatory movement in the plane of said cover.

3. A furnace cover operating mechanism for a furnace chamber or the like which opens upwardly, comprising in combination, a furnace cover lying substantially in a horizontal plane and adapted to close said opening when in operative position, said furnace cover being further adapted to be substantially entirely removed from said opening by translatory movement only substantially in the plane of said cover, generally horizontal and parallel rigid tracks spaced on opposite sides of said opening, said tracks extending beyond said opening a distance at least equal to the length of said cover in the direction of its movement, at least one pair of spaced wheels on one side of said cover and at least one wheel on the opposite side of said cover, said wheels adapted to be supported on said tracks during movement of said cover and to effect at least 3-point stable suspension, hydraulic means for simultaneously elevating said tracks at at least the end thereof adjacent said opening when said cover is in operative position to cause said tracks to engage said wheels and lift said cover off said furnace chamber opening, said hydraulic means being further adapted to lower said tracks at at least said end adjacent said opening after said furnace cover has been recharged and said cover returned to a position over said opening in order to lower said cover into operative position and to disengage said tracks from said wheels, stops on at least one of said tracks to limit the translatory movement of said cover, a lever substantially positioned in a vertical plane about midway between said tracks and below said cover, said lever being pivotally fixed adjacent its lower end, an adjustable link connecting said lever adjacent its upper end to said cover, said lever being adapted to swing to effect said translatory movement of said cover, said lever further being away from said opening in the direction of removal of said cover therefrom, and hydraulic means for swinging said lever after said tracks have been elevated to effect such translatory removal of said cover from a position above its operative position, whereby said cover in operative position closes said opening irrespective of any warpage in said tracks and may be removed without excessive friction or extending substantially above its normal operative position.
